ESCAPEMENT

Jean Bourquin, Waldenburg, Switzerland, assignor to Institut Dr. Ing. Reinhard Straumann A.G., Basel-Campagne, Switzerland, a Swiss company

Filed Apr. 6, 1959, Ser. No. 804,251

Claims priority, application Switzerland Apr. 30, 1957
7 Claims. (Cl. 58—121)

This invention relates to parts of clock and watch movements which have surfaces which are in sliding contact, and it relates particularly to parts of the escapement mechanism of clock and watch movements.

Such parts are at present usually made of brass and sometimes of steel. When such parts are made in the conventional manner, difficulties frequently arise, because the unsatisfactory properties of the materials as regards their ability to slide on one another cause friction between the surfaces in sliding contact to increase, or because the surfaces which are in sliding contact corrode or pit and thus adversely affect the running of the clock or watch.

According to the disclosure in a copending application Serial No. 711,214 in the name of F. Straumann and H. Bourquin, and relating to self-winding watches, the properties of the coating surfaces of barrel and mainspring which cause them to slide on each other, which parts, as is known, constitute a slip coupling, can be improved by making the barrel of anodically oxidized aluminum. The surface layer thus produced has better frictional properties and corrosion or pitting of the sliding surfaces does not occur.

It is also conventional in watches and clock mechanisms to use bearings of anodized aluminum in combination with steel shafts or pointed steel bearings.

The present invention however, relates neither to bearings nor to spring barrels, but to escapement mechanisms.

It is an object of the present invention not only to reduce the inertia of escapement parts in clock and watch movements of all kinds, such as for instance the inertia of the escape wheel, pallet and anchor, but also to improve the mechanical and physical properties of these parts of clocks and watches by making these parts of an anodically oxidizable aluminum or an anodically oxidizable aluminum alloy.

It is a further object of the present invention to provide an escapement mechanism in which the large moving parts are of an anodically oxidized aluminum or aluminum alloy, and the parts bearing on said large moving parts are of a rustproof alloy taken from the group consisting of iron-cobalt, iron-nickel-chromium, and iron-nickel-cobalt-chromium alloys, which alloys have been heat treated to have a tensile strength of at least 180 kg./mm.² and a Vickers hardness of above 650 kg./mm.².

An advantage of this combination of friction surfaces, one of an anodically oxidized aluminum or aluminum alloy and the other of a rustproof alloy which has a tensile strength of at least 180 kg./mm.² and a Vickers hardness of above 650 kg./mm.², is that it exhibits the best frictional properties and in such a combination no corrosion occurs.

Another advantage of having parts consisting of aluminum or an aluminum alloy is that the weight is less than when the parts consist of heavy metal alloys, so that their inertia is lower, and they therefore require less energy to keep them in motion. Moreover, due to the lower weight, bearing pressures and friction are also reduced.

Still another advantage is that parts of clocks and watches made, according to the invention of aluminum alloys are largely corrosion resistant and non-magnetic and they can also be easily machined.

Moreover, it is known in the art that an important dis-

2

advantage of escapement mechanisms having an escape wheel of brass and anchor pins of steel is that after a certain time a constantly increasing layer of black paste forms on the anchor pins, which paste consists of old oil

5 and metal particles formed by abrasion and dust, and which impairs the accurate functioning of the watch. With the combination of parts according to the present invention the anodically oxidized parts are rustproof, and substantially fewer metal abrasion particles accumulate so 10 that the accurate operation of the watch continues for a longer period of time than heretofore. Any oil which might be present would thicken the dust. Extensive experiments have shown that it is possible for an escapement mechanism to operate without oil lubrication. 15 Therefore, in the mechanism according to the invention the parts can operate either without any lubrication, or an oil free lubrication system can be used such as a system in which the parts are coated with a plastic layer less than one micron in thickness containing carbon monofluorid as 20 a lubricant. Alternatively, the layer can be a film of soap or a detergent. A somewhat different lubrication system which is possible is one in which the parts are coated with a tightly adhering, non-sticky coating of a plastic containing a high pressure lubricant. This may for example be a salt of stearic acid. A still further possibility is a lubrication system which is created by causing the surface of the parts which are to be in sliding frictional contact to adsorb a vapor which will act as a lubricant by surrounding them with the said vapor.

25 30 The fact that the escapement mechanism according to the invention operates without oil, and may even operate without any lubrication means at all, is an unusually important advance as regards escapements.

The attached drawings show an embodiment of the 35 present invention. In the drawings:

FIG. 1 is a top plan view of an escapement mechanism of a watch; and

FIG. 2 is a section on line II—II of FIG. 1, but on an enlarged scale.

40 45 The anchor 1 is pivoted, for example on a frame (not shown) on a pin 2. It is provided with two anchor pins 3 and 4 which retard the escape wheel 5 and release it to transmit the impulses from the escape wheel through the anchor to the balance wheel. The escape wheel 5 is mounted on shaft 6. A balance wheel shaft 7 is also provided. On one end of balance wheel shaft 7 is a roller 8 to which one end of the spiral spring 9 is fastened. The other end of spiral spring 9 is connected to the working plate (not shown in the drawing) by the small block 10. Below the roller 8 on the balance shaft 7 is mounted the balance wheel 11, one part of which is broken away in the drawing. Below the balance wheel is located the lifting cylinder 12 which is formed from a single body together with the safety cylinder 13. The lifting cylinder 12 carries the lifting pin 14, which fits into the notch 15 of the fork 16 forming one part of the anchor 1. To the fork 16 is riveted the safety knife 17 which, together with the safety roller 13 prevents recoil of the anchor.

50 55 This construction of such an anchor escapement mechanism is known in the art, so that a detailed description of the operation of the mechanism would be superfluous. It is sufficient for the present purpose to state that in said anchor escapement mechanism on the one hand the escape wheel 5 slidingly engages the pins 3 and 4, and on the other hand the fork 16 slidingly engages the lifting pin 14.

60 65 When manufacturing such a mechanism according to the present invention, the escape wheel 5 and the anchor 1 are made from aluminum or an aluminum alloy and the finished parts anodically oxidized, so that they have an anodically oxidized surface layer. The pins 3 and 4 as well as the lifting pin 14 are made of a rustproof alloy.

Aluminum alloys suitable for the escapement wheel and

the pallet fork according to the invention include hardenable alloys such as those of the compositions given in Table A.

Table A

	I	II	III
	Percent	Percent	Percent
Cr			0.1-1
Co		3.5-5	1-2.5
Mg	0.5-1	0.2-1.5	2-3
Mn	0.2-1	0.2-1.5	0.2-1
Si	0.5-1.5	0-1	
Zn			5.5-7
Al	Rest	Rest	Rest

For improving their mechanical strength these alloys may advantageously be subjected to a suitable heat treatment. For instance, the strength of alloy I can be improved by quenching the alloy from a temperature range of 530° C. to 550° C. down to about room temperature and age hardening it at a temperature of 155° C. to 160° C. for about 4 hours. The strength of alloy II can be improved by quenching it from the temperature range of 505° C. to 515° C. down to about room temperature and aging it at room temperature for about 100 hours. The strength of alloy III can be improved by heating the said alloy within the temperature range of 400° C. to 440° C. for about 5 hours, followed—with or without a quenching operation to about room temperature—by heating the alloy for 4 to 8 hours at between 250° C. and 340° C.

As a rustproof material for the pins which have surfaces in sliding contact with the anodically oxidized aluminum, among others, the alloys of Table B can be used.

temperature of 420° C. for the Vickers hardness increases until at least 650 kg./mm.². The desired form of the work piece can be achieved by turning, cutting or grinding.

5 If there is used a sheet metal as starting material, it can be heat treated at 1050° C., quenched in water, and cold rolled to get a reduction of cross section of 90%, the desired parts can be worked out, for instance by punching, and annealed during 2 hours at 450° C.

10 Using one of the alloys 6-11, the material is heat treated preferably at a temperature of 1150° C. in air or in a protective atmosphere and quenched in water. After cold deformation to receive a reduction of cross section of 80-95%, the parts will be worked out and annealed during 15 4 hours at a temperature of 480° C. for reaching a Vickers hardness of about 700 kg./mm.².

15 This application is a continuation-in-part of United States application Serial No. 731,096, filed April 28, 1958, now abandoned.

20 I claim:

1. In a watch mechanism, the combination of an oscillatingly movable part of an anodically oxidized metal taken from the group consisting of aluminum and hardenable aluminum alloys, and a further part with which said movable part is in sliding frictional contact for at least part of the oscillatory movement of said movable part, said further part being of a heat treated and cold worked rustproof alloy having a tensile strength of at least 180 kg./mm.² and a Vickers hardness of over 650 kg./mm.² said alloy being an alloy taken from the group of precipitation hardenable 42-48% iron—27-33% cobalt alloys having minor percentages of other metals therein, precipitation hardenable 3-17% iron—14.5-26.5% nickel—

From each of these alloys can be manufactured pins which, after a suitable heat treatment, have a tensile strength of at least 180 kg./mm.² and a Vickers hardness of above 650 kg./mm.².

By cold-forming these alloys in an amount which reduces the cross section of the material being formed up to 90% and more, ultimate stress values of above 180 kg./mm.² can also be obtained which are favorable for such a pin, as well as coefficients of hardness of above 650 kg./mm.².

The material has to be treated according to the type of alloy so that the finished parts reach the necessary tensile strength and the desired Vickers hardness.

For the manufacturing of parts from the alloy No. 1 one uses a piece of said material which is to be treated at 900° C. during 5 hours and then cooled down slowly. Afterwards it will be heat treated during 15 minutes at a temperature of 1250° C. and quenched in a lead bath of 600° C. After cooling in air there will be given the desired form to it by metal cutting. For reaching a Vickers hardness of about 1000 kg./mm.² the parts are to be annealed during 20 minutes at a temperature of 600° C.

To manufacture pins and the like of one of the alloys 2-5 one takes as starting material a wire. After heat treating it during 15 minutes at a temperature of 1000° C. the wire is quenched in water and cold-drawn until the reduction of cross section is about 90%. Then, the material is straightened and annealed during 4 hours at a

25-65% cobalt—8-22% chromium alloys having minor percentages of other metals therein, and precipitation hardenable 58-62% nickel—14-18% iron—and 13.5-16.5% chromium alloys having minor percentages of other metals therein.

2. In a watch mechanism, the combination of an oscillatingly movable part of an anodically oxidized metal taken from the group consisting of aluminum and quenchable and age hardenable aluminum-magnesium-manganese alloys, and a further part with which said movable part is in sliding frictional contact for at least part of the oscillatory movement of said movable part, said further part being of a heat treated and cold worked rustproof alloy having a tensile strength of at least 180 kg./mm.² and a Vickers hardness of over 650 kg./mm.² said alloy being an alloy taken from the group of precipitation hardenable 42-48% iron—27-33% cobalt alloys having minor percentages of other metals therein, precipitation hardenable 3-17% iron—14.5-26.5% nickel—25-65% cobalt—8-22% chromium alloys having minor percentages of other metals therein, and precipitation hardenable 58-62% nickel—14-18% iron—and 13.5-16.5% chromium alloys having minor percentages of other metals therein.

3. In an escapement mechanism for a watch, the combination of an anchor of an anodically oxidized metal taken from the group consisting of aluminum and hardenable aluminum alloys, and a lifting pin with which said anchor is in sliding frictional contact for at least part of

the oscillatory movement of said anchor, said lifting pin being of a heat treated and cold worked rustproof alloy having a tensile strength of at least 180 kg./mm.² and a Vickers hardness of over 650 kg./mm.² said alloy being an alloy taken from the group of precipitation hardenable 42-48% iron-27-33% cobalt alloys having minor percentages of other metals therein, precipitation hardenable 3-17% iron-14.5-26.5% nickel-25-65% cobalt-8-22% chromium alloys having minor percentages of other metals therein, and precipitation hardenable 58-62% nickel-14-18% iron-13.5-16.5% chromium alloys having minor percentages of other metals therein.

4. In an escapement mechanism for a watch, the combination of an escape wheel of an anodically oxidized metal taken from the group consisting of aluminum and hardenable aluminum alloys, and a plurality of anchor pins with which said escape wheel is in sliding frictional contact for at least part of the oscillatory movement of said escape wheel, said anchor pins being of a heat treated and cold worked rust-proof alloy having a tensile strength of at least 180 kg./mm.² and a Vickers hardness of over 650 kg./mm.² said alloy being an alloy taken from the group of precipitation hardenable 42-48% iron-27-33% cobalt alloys having minor percentages of other metals therein, precipitation hardenable 3-17% iron-14.5-26.5% nickel-25-65% cobalt-8-22% chromium alloys having minor percentages of other metals therein, and precipitation hardenable 58-62% nickel-14-18% iron- and 13.5-16.5% chromium alloys having minor percentages of other metals therein.

5. The combination as claimed in claim 1 in which said anodically oxidized metal has the composition

Mg	-----	0.5%-1%
Mn	-----	0.2%-1%
5 Si	-----	0.5%-1.5%
Al	-----	Rest

6. The combination as claimed in claim 1 in which said anodically oxidized metal has the composition

10 Cu	-----	3.5%-5%
Mg	-----	0.2%-1.5%
Mn	-----	0.2%-1.5%
Si	-----	0-1%
Al	-----	Rest

15 7. The combination as claimed in claim 1 in which said anodically oxidized metal has the composition

Cr	-----	0.1%-1%
Cu	-----	1%-2.5%
Mg	-----	2%-3%
20 Mn	-----	0.2%-1%
Zn	-----	5.5%-7%
Al	-----	Rest
